CONVERSION OF HYDROCARBON OILS

Charles H. Angell, Chicago, Ill., assignor to Universal Oil Products Company, Chicago, Ill., a corporation of Delaware

Application June 8, 1934, Serial No. 729,542

15 Claims. (Cl. 196—49)

This invention particularly refers to an improved process for the fractional distillation of hydrocarbon oils of relatively wide boiling range accompanied by the pyrolytic conversion of intermediate or high-boiling fractions of the charging stock and intermediate conversion products of the process; coking of the residual liquid conversion products, either alone or together with high-boiling fractions of the charging stock, and reforming of any inferior motor fuel fractions of the charging stock and of the vaporous products of the coking operation for the purpose of producing, primarily, high yields of motor fuel of good antiknock value.

Many processes have been proposed, some of which are now in use, for the coking, at relatively low pressure, of residual liquids resulting from the pyrolytic conversion of hydrocarbon oils at relatively high pressure. Many such coking operations are accomplished simultaneous and in direct cooperation with the cracking process wherein the residual oil is produced and such operations are of great economic importance at the present time, due to the ability to produce, by their use, high yields of desirable light liquid products, such as motor fuel, with relatively low yields of residue, which is in the form of substantially dry coke and is marketable as domestic fuel. It has been found, however, that the motor fuel recovered by fractionation of the vaporous products from such low-pressure coking operations is often of inferior quality, particularly with respect to its antiknock value. Furthermore, it is readily apparent that, due to the high temperatures required for reduction of residual oil to low volatile coke, the resulting vaporous products contain a considerably greater quantity of heat than is necessary for their fractionation and this excess heat is ordinarily dissipated without being employed to advantage.

In the present invention the excess heat from the low-pressure coking operation, such as above mentioned, is utilized to advantage by employing the same to effect fractional distillation of hydrocarbon oil charging stock for the process and the unsatisfactory motor fuel components of the vaporous products from the coking operation, together with any motor fuel components of the charging stock of poor antiknock value, are subjected to reforming for the purpose of materially improving their motor fuel characteristics without excessively altering their boiling range, thereby obviating both of the disadvantages above mentioned which ordinarily at-

tend the coking of residual liquid conversion products at low temperature.

Another disadvantage ordinarily encountered in low-pressure coking operations is the presence of appreciable amounts of relatively heavy high coke-forming materials, including entrained tars, pitches and the like in the vaporous products from the coking operation. These materials contaminate the reflux condensate unless removed from the vapors, prior to their fractionation for the formation of reflux condensate, and ordinarily cause excessive coking if returned to a heating coil for further conversion, together with the reflux condensate. The present invention provides for the removal of such high-coke-forming materials from the vaporous products of the coking operation by contact with hydrocarbon oil charging stock for the process accompanied by collection of such materials, together with any similar high coke-forming components of the charging stock, separate from the lower boiling reflux condensate and lower boiling components of the charging stock and further provides for the return of the high coke-forming materials to the coking stage of the process.

The present invention embodies numerous other cooperative features and advantages which will be more apparent with reference to the subsequent description. It will be understood, however, that the invention is not limited to any one or any combination of the minor features described but is directed, primarily, to the cooperative relation between the coking, topping and reforming operations whereby the charging stock is subjected to fractional distillation by means of heat recovered from the coking operation and unsatisfactory motor fuel components of the charging stock and of the vaporous products from the coking operation are commingled and subjected to reforming.

In one specific embodiment, the invention comprises subjecting a hydrocarbon oil charging stock of relatively wide boiling range to fractional distillation, recovering any desirable components of the charging stock such as motor fuel fractions of satisfactory antiknock value, subjecting high-boiling fractions of the charging stock boiling above the range of motor fuel and selected low-boiling fractions of the charging stock, including any motor fuel components of unsatisfactory antiknock value, each to independently controlled conversion conditions of elevated temperature and superatmospheric pressure for the production of high yields of motor fuel of good antiknock value, separating the resulting

vaporous and liquid conversion products, subjecting the latter to further vaporization at substantially reduced pressure relative to that at which they are formed, subjecting the vaporous conversion products to fractionation whereby their insufficiently converted components are condensed as reflux condensate, returning the reflux condensate to further conversion in the same system, subjecting fractionated vapors of the desired end-boiling point to condensation and recovering the resulting distillate, subjecting the residual liquid conversion products remaining unvaporized by said further vaporization to further heating and to coking in a zone of relatively low pressure, subjecting vaporous products from the coking zone to fractionation together with the hydrocarbon oil charging stock and returning high coke-forming materials removed from the vaporous products of the coking operation, together with any similar high coke-forming components of the charging stock to the coking stage.

Many modifications of the above specific embodiment are possible within the scope of the present invention. Some of these, as well as the operation above outlined, are described in connection with the following description of the accompanying diagrammatic drawing. The drawing illustrates one specific form of apparatus in which the process of the invention may be accomplished.

Referring to the drawing, hydrocarbon oil charging stock for the process, preferably comprising oil of relatively wide boiling range, such as, for example, crude petroleum or the like, containing a substantial quantity of materials within the boiling range of motor fuel which are of unsatisfactory antiknock value, may be supplied through line 1 and valve 2 to pump 3 by means of which it may be fed through line 4 and valve 5 into distilling and fractionating column 6, wherein it is subjected to fractional distillation, together with vaporous products from the coking stage of the process supplied to this zone as will be later more fully described. The charging stock may, of course, be preheated by any well known means, not illustrated, prior to its introduction into column 6, however, the major portion of the heat required for fractional distillation of the charging stock may ordinarily be recovered from the vaporous products of the coking operation and use of the charging stock, in the manner illustrated and described, serves to cool and assist fractionation of said vapors.

Fractionated vapors of the desired end-boiling point, preferably comprising materials within the boiling range of motor fuel and, when desired, somewhat higher boiling materials such as naphtha, kerosene or kerosene distillate, pressure distillate bottoms and the like, are withdrawn, together with uncondensable gas, from the upper portion of column 6 through line 7 and valve 8 to be subjected to condensation and cooling in condenser 9. The resulting distillate and gas pass through line 10 and valve 11 to collection and separation in receiver 12. Uncondensable gas may be released from the receiver through line 13 and valve 14. Distillate may be withdrawn from receiver 12 through line 15 and valve 16 to storage or to any desired further treatment.

In case the materials subjected to fractionation in column 6, comprising the charging stock and vaporous products of the coking operation, contain no appreciable quantity of materials within the boiling range of motor fuel which are of satisfactory antiknock value, a regulated por-

tion or all of the condensate collected in receiver 12 is preferably withdrawn therefrom through line 17 and valve 18 to pump 19 by means of which it is supplied through line 20, valve 21 and line 22 to heating coil 23.

In case the materials subjected to fractionation in column 6 contain an appreciable quantity of materials within the boiling range of motor fuel having satisfactory motor fuel characteristics, particularly with respect to their antiknock value, these materials may be collected in receiver 12, as previously described, while somewhat higher boiling materials, including motor fuel fractions of unsatisfactory antiknock value or of otherwise inferior motor fuel quality as well as, when desired, somewhat higher boiling materials such as, for example, naphtha, kerosene or kerosene distillate, pressure distillate bottoms and the like may be separately withdrawn as one or a plurality of side streams from column 6 at any suitable intermediate point or points in this zone, passing, for example, through line 24, valve 25 and line 17 to pump 19 to be supplied therefrom to heating coil 23, in the manner previously described.

It is, of course, also within the scope of the present invention, in case the overhead product from column 6 is supplied to heating coil 23, to supply the overhead vaporous product, including uncondensable gas, direct to the heating coil by suitable well known means, not illustrated, without first condensing the distillate and separating the gases in receiver 12, as previously described.

A furnace 26 of any suitable form supplies the required heat to the oil passing through heating coil 23 to bring it to the desired conversion temperature, preferably at a substantial superatmospheric pressure and, in the preferred embodiment of the invention, the heating coil and furnace arrangement is such that the relatively light oil supplied to heating coil 23 is brought to or near the maximum desired conversion temperature and then maintained at a temperature near the maximum to which it is subjected for a predetermined time. The stream of highly heated products is discharged from heating coil 23 through line 27 and may pass through valve 28 and valve 29 in this line into reaction chamber 30, being cooled, when desired, by means which will be later described, to a temperature at which its conversion is materially retarded or arrested, prior to its introduction into the reaction chamber, particularly in case a soaking section is employed in heating coil 23. Also, when desired, instead of introducing all of the heated products from heating coil 23 into reaction chamber 30 a regulated portion or all of this material may be supplied from line 27 through line 31 and valve 32 into vaporizing chamber 33. Further reference to this particular feature of the invention will be made later.

Reaction chamber 30 is also preferably maintained at a substantial superatmospheric pressure and, although not indicated in the drawing, is preferably insulated to prevent the excessive loss of heat so that conversion of relatively high-boiling oils, supplied to this zone as will be later described, as well as, when desired, the heated products from heating coil 23, may continue in the reaction chamber. In the case here illustrated, both vaporous and liquid conversion products are withdrawn from the lower portion of chamber 30 through line 34 and valve 35 and are introduced into vaporizing chamber 33 wherein further vaporization of the liquid conversion

products is accomplished. It is also within the scope of the invention to separately withdraw vaporous and liquid conversion products from the reaction chamber by well known means, not illustrated, in which case the liquid products, either alone or together with a regulated portion of the vapors, may be introduced into chamber 33 or the liquid conversion products may be supplied direct to heating coil 44 for further heating and subsequent reduction to coke while the vaporous products may be supplied, all or in part, to chamber 33 or to fractionator 38, although well known means for accomplishing these alternate operations are not illustrated in the drawing.

Chamber 33 is preferably operated at a substantially reduced pressure relative to that employed in chamber 30, whereby appreciable further vaporization of the liquid conversion products supplied to this zone is accomplished. Introduction of a regulated portion or all of the heated products from heating coil 23 into chamber 33, as previously described, may serve to assist further vaporization of the liquid conversion products in this zone and it is within the scope of the invention to supply heated products from heating coil 23 to chamber 33, at any desired point in this zone, with or without prior cooling of the same. Vaporous products are withdrawn from the upper portion of chamber 33 and supplied through line 36 and valve 37 to fractionation in fractionator 38 and, as already mentioned, when vaporous conversion products are separately withdrawn from chamber 33 they may also be supplied, when desired, direct to fractionator 38, although this is not indicated in the drawing. Residual liquid conversion products remaining unvaporized in chamber 33 are withdrawn from the lower portion of this zone through line 39 and valve 40 to pump 41 by means of which they may be supplied through line 42 and valve 43 to heating coil 44.

Heating coil 44 is located within a furnace 45 of any suitable form by means of which sufficient heat is imparted to the residual liquid passing through this zone to effect its subsequent reduction to substantially dry coke in coking chamber 46, to which the heated oil from heating coil 44 is supplied by means of line 47 and branch lines 48 controlled by valves 49, which permit the introduction of the hot residual oil into the coking chamber at any desired point or plurality of points in this zone. Preferably, the residual oil passing through heating coil 44 is subjected to relatively high rates of heating so that it may be brought quickly to the relatively high temperature required for its reduction to coke in the coking zone without allowing it to remain in heating coil 44 for a sufficient length of time to permit any appreciable formation and deposition of coke, prior to its introduction into the coking zone. This method of coking is not new in itself and is not claimed as a novel feature of the invention but constitutes a preferred method of coking in the present invention due to its cooperability with the other features of the invention, although it will be understood that other well known methods of coking may be employed, either alone or in conjunction with the method above described, without departing from the scope of the present invention.

It is, for example, specifically within the concept of the present invention to externally heat the coking chamber or to supply a suitable heat carrying medium thereto. The invention also contemplates the use of coking retorts employ-

ing a refractory heat conducting floor or wall and also the use of rotary coking retorts of the type wherein the coke is deposited on the internal surface of the retort walls or of the type wherein it is deposited on the external surface.

Coking chamber 46 is preferably operated at substantially atmospheric or a relatively low superatmospheric pressure, as low pressures favor the production of low volatile coke, and in case a substantially lower pressure is employed in the coking chamber than in vaporizing chamber 33 the use of pump 41 may be obviated. The coke produced in chamber 46 may be allowed to accumulate within this zone to be removed therefrom in any well known manner, not illustrated, after the operation of the chamber is completed. When desired, a plurality of coking chambers similar to chamber 46 may be employed, although not illustrated, and may be operated simultaneously or, preferably, are alternately operated, cleaned and prepared for further operation, so that the coking stage of the process, as well as the distilling and cracking stages, is continuous. Chamber 46 is provided with a suitable drain line 50 controlled by valve 51 which may also serve as a means of introducing suitable cooling material such as, for example, water and/or steam into the coking chamber, after its operation is completed and it has been isolated from the rest of the system, in order to hasten cooling and facilitate cleaning of the chamber.

The vaporous products of the coking operation may pass from the upper portion of chamber 46 through line 52 and valve 53 to fractionation in distilling and fractionating column 6, together with the charging stock supplied to this zone as previously described, the heat in the vaporous products from the coking zone serving as a means of effecting vaporization and fractionation of the charging stock while the charging stock serves as a cooling means to assist fractionation of the vaporous products from the coking zone. The components of the vaporous products from the coking chamber condensed in column 6, together with the high-boiling components of the charging stock which are condensed or remain unvaporized in the distilling and fractionating column, may be withdrawn from the lower portion of this zone through line 54 and valve 55 to pump 56 by means of which they are fed through line 57 and may be supplied through valve 58 to vaporizing chamber 33.

By this method of operation any high coke-forming materials contained in the vaporous products from the coking zone, including entrained particles of tar, pitch and the like as well as any similar high boiling components of the charging stock, are included in the condensate withdrawn from the lower portion of column 6 but are separated in chamber 33 from the lower boiling components of the condensate, which latter are vaporized in this zone and supplied therefrom to fractionation in fractionator 38. The high coke-forming materials in the condensate supplied from column 6 to chamber 33 commingle in the vaporizing chamber with the residual liquid conversion products and pass therewith to heating in heating coil 44 and to subsequent coking in chamber 46.

It is also within the scope of the invention, particularly in case the charging stock contains no appreciable quantity of heavy high coke-forming materials, to separate the heavy components of the vapors from the coking zone, in-

cluding entrained tars, pitches and the like, prior to fractionation of the vapors in column 6. This may be accomplished in any well known manner such as, for example, by indirect contact and heat exchange between the vaporous products from the coking chamber and the charging stock in a suitable partial condenser or heat exchanger, not illustrated, in which case the condensate from the heat exchanger or partial condenser may be returned either to vaporizing chamber 33, heating coil 44 or coking chamber 46, as desired. In case the latter type of operation is employed (separate removal of the high coke-forming materials from the vaporous products of the coking operation, prior to their fractionation in column 6) the condensate from column 6 may be returned, all or in part, to vaporizing chamber 33, as previously described, or may be supplied to fractionator 38 or commingled with the reflux condensate from fractionator 38 external to the fractionator and subjected to further treatment therewith, as will be later more fully described, although for the sake of simplicity the well known lines and valves for accomplishing these alternatives are not illustrated in the drawing.

By supplying all or a regulated portion of the condensate from column 6 to vaporizing chamber 33 this material may be utilized as a means of effecting condensation of some of the heavy vapors evolved from the residual liquid undergoing vaporization in chamber 33 and baffles or fractionating means of any suitable form, not illustrated, may be employed, when desired, in the upper portion of chamber 33 to assist rough fractionation of the evolved vapors. By regulation of the quantity of relatively cold condensate supplied from column 6 to chamber 33 and the quantity of relatively hot products from heating coil 23 supplied to this zone, the degree of vaporization in chamber 33 and the characteristics of the residual liquid withdrawn from this zone for coking may be accurately controlled and, when desired, the condensate supplied to chamber 33 may be cooled to any desired degree, by well known means not shown, prior to its introduction into the vaporizing chamber.

The components of the vaporous materials supplied, as previously described, to fractionator 38, boiling above the range of the desired final light distillate product of the process, are condensed in this zone as reflux condensate, which may be withdrawn as a single product from the fractionator or may be separated therein, as will be later more fully described, into selected relatively low-boiling and high-boiling fractions. Fractionated vapors of the desired end-boiling point, preferably comprising materials within the boiling range of motor fuel and of good antiknock value, are withdrawn, together with uncondensable gas, from the upper portion of fractionator 38 through line 59 and valve 60 to be subjected to condensation and cooling in condenser 61. The resulting distillate and gas passes through line 62 and valve 63 to collection and separation in receiver 64. Uncondensable gas may be released from the receiver through line 65 and valve 66. Distillate may be withdrawn from receiver 64 through line 67 and valve 68 to storage or to any desired further treatment.

The usual well known expedients for assisting fractionation of the vapors in column 6 and fractionator 38, such as, for example, returning regulated portions of the distillate from receivers 12 and 64 to the respective fractionating zones, may

be employed, although not illustrated in the drawing.

When the reflux condensate formed in fractionator 38 is separated, as previously mentioned, into selected relatively low-boiling and high-boiling fractions, selected high-boiling fractions may be withdrawn from any suitable intermediate point or plurality of points in the fractionator and supplied, for example, through line 89 and valve 70 to pump 71 by means of which they are fed through line 72 and may be directed through valve 73 in this line and through line 22 to further conversion in heating coil 23, together with low-boiling distillate from the distilling and coking operations, supplied to heating coil 23 as previously described, or the selected low-boiling condensate from fractionator 38 may be diverted from line 72 through line 74 and directed through valve 75 to further conversion in heating coil 16.

The high-boiling fractions of the reflux condensate formed in fractionator 38 or the total reflux condensate, in case selected low-boiling fractions are not separately withdrawn from this zone, may be withdrawn from the lower portion of the fractionator through line 77 and valve 78 to pump 80 by means of which this material is fed through line 81 and may be directed through valve 88 and line 74 to further conversion in heating coil 16 or, when desired, a regulated portion or all of this material may be directed from line 81 through line 89 and valve 90 into line 27 to commingle therein with the stream of hot conversion products from heating coil 23.

When the latter method of operation is employed the temperature to which the reflux condensate from fractionator 38 is heated by commingling with the stream of heated products from heating coil 23 may be sufficient to effect appreciable further conversion of the reflux condensate but preferably the temperature of the resulting stream of commingled materials is sufficiently low to prevent excessive conversion of the reflux condensate as well as excessive further conversion of the heated products from heating coil 23. The commingled materials are preferably directed through line 27 and valve 28 into reaction chamber 30 but may, when desired, be directed all or in part from line 27 through line 31 and valve 32 into vaporizing chamber 33.

In case reflux condensate from fractionator 38 is commingled, as described, with the stream of highly heated products from heating coil 23, heating coil 16 or reaction chamber 30, or both of these zones may be eliminated, although it is specifically within the scope of the invention to supply only high-boiling fractions of the reflux condensate to line 27 and to subject selected low-boiling fractions of the reflux condensate from fractionator 38 to further conversion in heating coil 16 and reaction chamber 30.

The oil supplied to heating coil 16, comprising the total or regulated portions of the total reflux condensate from fractionator 38 or selected low-boiling fractions of the reflux condensate from fractionator 38, is subjected, by means of heat supplied from a furnace 91 of any suitable form, to the desired conversion temperature, preferably at a substantial superatmospheric pressure, and the heated products from heating coil 16 may be directed through line 02 and valve 03 into reaction chamber 30 or may, when desired, be supplied by well known means not illustrated, to vaporizing chamber 33.

It will be understood that the many alternative methods of operation above described are not to

be considered equivalent but may be selected to suit requirements, depending upon the type of oil being treated, the desired results and the particular operating conditions employed. The alternative features mentioned are, in many cases, not new in themselves but are complementary to the main features and objects of the invention and are intended to broaden rather than to limit its scope.

10 Equipment and lines necessary for accomplishing many of the alternative features of the invention are, for the sake of simplicity, omitted from the drawing but their use will be readily understood from the description by those familiar 15 with the art without the necessity of illustration. Many other departures from the specific process and apparatus described and illustrated will be readily apparent and may be employed without departing from the spirit and scope of the invention.

20 In an apparatus such as illustrated and above described, the preferred range of operating conditions may be approximately as follows: The heating coil to which the selected relatively low-boiling fractions of the charging stock and of the 25 vaporous products from the coking operation are supplied may utilize a maximum conversion temperature ranging, for example, from 950 to 1050° F., preferably with a superatmospheric pressure, 30 measured at the outlet from the heating coil, of from 300 to 1000 pounds, or thereabouts, per sq. in. The heating coil to which the total reflux condensate or regulated portions of the total reflux condensate or selected low-boiling fractions 35 of the reflux condensate from the fractionator of the cracking system are supplied, when this heating coil is employed, may utilize a conversion temperature, measured at the outlet from this zone, of from 800 to 950° F., or thereabouts, preferably with a superatmospheric pressure at this 40 point in the system of from 100 to 500 pounds, or more, per sq. in. The reaction chamber when utilized may employ any desired pressure ranging from 100 to 500 pounds, or more, per sq. in., 45 while the vaporizing chamber may be operated at a pressure ranging, for example, from substantially atmospheric to 100 pounds, or thereabouts, per sq. in., with substantially equalized or somewhat reduced pressures in 50 the succeeding fractionating, condensing and collecting equipment. The temperature to which the residual liquid is heated to effect its reduction to coke may range, for example, from 900 to 975° F., or thereabouts, preferably with a superatmospheric pressure of from 50 to 150 pounds, or 55 thereabouts, in the heating coil and, as previously mentioned, relatively rapid rates of heating and a relatively short time factor are preferred in this zone. The coking chamber is preferably operated 60 at a relatively low pressure ranging, for example, from substantially atmospheric to 100 pounds, or thereabouts, per sq. in. while the succeeding fractionating and distilling equipment may be operated at substantially the same or somewhat lower 65 pressure than that employed in the coking chamber.

As a specific example of one of the many possible operations of the process of the present invention, as it may be accomplished in an apparatus such as illustrated and above described, the charging stock, which comprises a California crude of about 27.5° A. P. I. gravity, containing about 5 percent of material boiling up to 220° F. and about 27 percent at 437° F., is subjected to 70 fractionation, together with vaporous products

from the coking stage of the process. Fractions of the crude and of the vaporous products of the coking operation boiling up to approximately 500° F., are subjected in a reforming coil to a conversion temperature of approximately 980° F. at a superatmospheric pressure of about 1000 pounds per sq. in. The resulting products are cooled to a temperature of about 900° F. by commingling therewith selected high-boiling fractions of the reflux condensate from the fractionator of the 10 cracking stage of the system and by reduction in pressure to about 350 pounds per sq. in., the commingled materials being introduced into a reaction chamber operated at about this pressure. Selected low-boiling fractions of the reflux condensate from the fractionator of the cracking stage are subjected in a separate heating coil to an outlet conversion temperature of approximately 950° F. at a superatmospheric pressure of about 400 pounds per sq. in. and the heated products 15 from this coil are also supplied to the reaction chamber. Vaporous and liquid conversion products are withdrawn from the reaction chamber in commingled state and are introduced into a vaporizing chamber operated at a reduced superatmospheric pressure of about 60 pounds per sq. in. Higher boiling components of the charging stock and of the vaporous products from the coking zone, including high coke-forming materials contained in the vapors from the coking 20 zone, are supplied to the vaporizing chamber wherein the high-boiling materials commingle with the residual liquid conversion products remaining unvaporized in this zone. Vaporous products from the vaporizing chamber are 25 subjected to fractionation for the formation of said low-boiling and high-boiling reflux condensates and fractionated vapors, which latter are subjected to condensation and the resulting distillate, comprising the final motor fuel product of 30 the process, is recovered. The residual liquid from the vaporizing chamber is quickly heated in a separate heating coil to a temperature of approximately 935° F. at a superatmospheric pressure of about 100 pounds per sq. in. and the heated residue is introduced into the coking chamber 35 which is operated at a superatmospheric pressure of about 30 pounds per sq. in. This operation may yield, per barrel of charging stock, approximately 67 percent of motor fuel having an octane 40 number of about 70 and about 60 pounds of petroleum coke of uniformly good structure, having a volatile content of less than five percent, the remainder being chargeable, principally, to uncondensable gas. 45

I claim as my invention:

1. In a process for the conversion of hydrocarbon oils wherein hydrocarbon oil is subjected to conversion conditions of elevated temperature and superatmospheric pressure in a cracking 60 zone, the resulting residual liquid and vaporous conversion products separated in a reduced pressure separating zone, the vapors subjected to fractionation for the formation of reflux condensate and the recovery of desirable low-boiling 65 components and the residual liquid subjected to additional heating, to effect its reduction to coke in a zone separate from that wherein the aforementioned residual liquid and vaporous conversion products are separated, the improvement 70 which comprises subjecting hydrocarbon oil charging stock for the process to fractional distillation by means of heat derived from the vaporous products of the coking operation, subjecting the vaporous products of the coking opera- 75

- tion to fractionation, subjecting selected relatively high-boiling components of the charging stock and of the vaporous products of the coking operation to said conversion in said cracking zone
- 5 5 subjecting selected relatively low-boiling components comprising the total motor fuel boiling component of the charging stock and of the vaporous products of the coking operation to independently controlled more severe conversion conditions, and commingling products of the last-named conversion stage with products of the first-mentioned conversion stage.
2. A process of the character defined in claim 1 wherein the selected low-boiling fractions of the charging stock and of the vaporous products of the coking operation supplied to the last mentioned conversion stage also include materials boiling somewhat above the range of motor fuel.
3. In a process for the conversion of hydrocarbon oils wherein the oil is subjected to conversion temperature at superatmospheric pressure in a heating coil and communicating reaction chamber, the resulting vaporous and liquid conversion products separated, the latter subjected to further vaporization in a vaporizing chamber operated at substantially reduced pressure, the vaporous conversion products, including those resulting from said further vaporization, subjected to fractionation for the formation of reflux condensate which is subjected to further conversion in the same system, fractionated vapors of the desired end-boiling point subjected to condensation, the resulting distillate recovered, non-vaporous residual liquid withdrawn from said vaporizing chamber and subjected to additional heating to effect its reduction to coke, the improvement which comprises directly commingling the vaporous products of the coking operation with hydrocarbon oil charging stock for the process, subjecting the commingled materials to fractionation, separate from the aforementioned vaporous conversion products, whereby they are separated into components comprising low-boiling motor fuel fractions of satisfactory antiknock value, selected somewhat higher boiling fractions, including motor fuel components of unsatisfactory antiknock value, intermediate fractions, boiling substantially entirely above the range of motor fuel, and still higher boiling components including 40 tars and similar high coke-forming materials, returning the high-boiling components, including tars and similar high coke-forming materials, to the coking operation, returning the intermediate fractions boiling substantially entirely above the range of motor fuel to the heating coil for further conversion, recovering the low-boiling motor fuel fractions of satisfactory antiknock value, subjecting the selected fractions including motor fuel components of unsatisfactory antiknock value to independently controlled conversion conditions, in a separate heating coil regulated to materially improve their motor fuel characteristics and commingling the products from said separate heating coil with the aforementioned vaporous conversion products, prior to their fractionation.
4. A process of the character defined in claim 3 wherein the reflux condensate resulting from the first mentioned fractionation is separated into selected relatively low-boiling and high-boiling fractions, the high-boiling fractions returned to the first mentioned heating coil for further conversion and the low-boiling fractions returned for further conversion to said separate heating coil.
5. A process of the character defined in claim 3 wherein the reflux condensate resulting from the
- first mentioned fractionation is separated into selected relatively low-boiling and high-boiling fractions, the low-boiling fractions returned for further conversion to the first mentioned heating coil and the high-boiling fractions commingled with the stream of heated products discharged from said separate heating coil.
6. A process of the character defined in claim 3 wherein the reflux condensate resulting from the first mentioned fractionation is returned for further conversion to the first mentioned heating coil.
7. A process of the character defined in claim 3 wherein the reflux condensate resulting from the first mentioned fractionation is commingled with the stream of heated products discharged from said separate heating coil.
8. A process of the character defined in claim 3 wherein the products from said separate heating coil are discharged into the reaction chamber.
9. A process of the character defined in claim 3 wherein the products from said separate heating coil are discharged into the vaporizing chamber.
10. A process of the character defined in claim 3 wherein said intermediate fractions of the commingled charging stock and vaporous products of the coking operation and their high-boiling components, including tars and similar high coke-forming materials, are returned to the vaporizing chamber.
11. In a process for the conversion of hydrocarbon oils wherein a relatively low-boiling oil recovered from within the system is subjected to a high conversion temperature at superatmospheric pressure in a heating coil, the resulting highly heated products cooled sufficiently to retard their excessive further conversion by commingling cooler hydrocarbon oil therewith, the commingled materials subjected to vaporization, the resulting residual liquid and vaporous products separated, the vapors subjected to fractionation for the formation of reflux condensate which is subjected to further conversion in the same system, fractionated vapors of the desired end-boiling point subjected to condensation, the resulting distillate recovered, and the non-vaporous residual liquid subjected to additional heating to effect its reduction to coke, the improvement which comprises commingling vaporous products from the coking operation with hydrocarbon oil charging stock for the process, separating the commingled materials into components comprising any low-boiling motor fuel fractions of satisfactory antiknock value, selected low-boiling fractions including any motor fuel components of unsatisfactory antiknock value, intermediate fractions boiling substantially entirely above the boiling range of motor fuel and any higher boiling components including tars and similar high coke-forming materials, returning the high-boiling components, including tars and similar high coke-forming materials, to the coking operation, recovering the low-boiling motor fuel fractions of satisfactory antiknock value, supplying the selected low-boiling fractions to said heating coil and commingling the intermediate fractions with the stream of highly heated products discharged from the heating coil.
12. A process of the character defined in claim 11 wherein said reflux condensate is commingled with the stream of highly heated products discharged from the heating coil.
13. A process of the character defined in claim 11 wherein said reflux condensate is separated into selected relatively low-boiling and high-boil-

ing fractions, the high-boiling fractions commingled with the stream of highly heated products discharged from the heating coil and the low-boiling fractions returned to the heating coil, 5 together with said selected low-boiling fractions of the commingled charging stock and vaporous products of the coking operation.

14. A conversion process which comprises heating hydrocarbon oil to cracking temperature under pressure in a heating coil and subsequently introducing the same to an enlarged separating zone, separating vapors from unvaporized oil in the separating zone, removing the unvaporized oil and subjecting the same to further distillation 10 in a second enlarged zone, fractionating vapors thus evolved in said second zone in contact with charging oil for the process thereby forming a mixture of condensate and unvaporized charging oil, separating from the contacting charging oil 15 and vapors undergoing fractionation a fraction of lower boiling point than said mixture, heating this fraction in a second heating coil to higher cracking temperature than the oil in the first-named coil and subsequently introducing the same into the first-named separating zone, introducing said mixture into the first-named separating zone and distilling a substantial portion thereof in this zone, removing resultant vapors from the first-named separating zone in admixture 20 with the first-mentioned vapors, fractionating these vapors and supplying resultant reflux condensate to the first-named heating coil, and

finally condensing the vapors uncondensed in the last-mentioned fractionating step.

15. A hydrocarbon oil conversion process which comprises separating cracked products, formed as hereinafter set forth, into vapors and residual liquid in a separating zone, distilling the residual liquid to coke in a coking zone, fractionating the vapors from the coking zone in contact with charging oil for the process thereby forming a mixture of heavy condensate and unvaporized 10 charging oil, separating from the contacting charging oil and vapors undergoing fractionation a fraction of lower boiling point than said mixture, introducing said mixture to the separating zone and therein distilling a substantial portion 15 thereof, passing said fraction of lower boiling point than the mixture through a heating coil and heating the same therein to cracking temperature under pressure, removing the vapors from the separating zone and fractionating the 20 same to form a relatively heavy reflux condensate and a lighter reflux condensate, subjecting the latter to independently controlled cracking conditions of temperature and pressure in a second heating coil, subjecting the heavy reflux condensate to cracking conditions by commingling the same with the heated products from said coils, introducing the resultant mixture to the separating zone as said cracked products, and finally 25 condensing the fractionated vapors. 30
